[57] CLAIM

The ornamental design for a computer mouse, as shown and described.

DESCRIPTION

FIG. 1 is a perspective view of a computer mouse showing our new design having dual activator buttons;

FIG. 2 is a top plan view thereof;

FIG. 3 is a rear elevational view thereof;

FIG. 4 is a right side elevational view, the left side elevational view being a mirror image;

FIG. 5 is a front elevational view thereof;

FIG. 6 is a front bottom plan view thereof;

FIG. 7 is a perspective view of a computer mouse showing our new design for an alternate preferred embodiment having a single activator button wherein FIG. 3 and FIG. 6 are views of the rear and bottom, respectively, of the alternate preferred embodiment;

FIG. 8 is a top plan view of the alternate embodiment;

FIG. 9 is a front elevational view of the alternate embodiment; and,

FIG. 10 is a right side elevational view, the left side elevational view being a mirror image of the alternate embodiment.
